UNITED STATES PATENT OFFICE.

EDWIN A. PETERSON, OF MADISON, WISCONSIN, ASSIGNOR TO THE SMITH-LEE COMPANY, OF ONEIDA, NEW YORK, A PARTNERSHIP COMPOSED OF WILBERT L. SMITH, HURLBUT W. SMITH, AND THE ESTATE OF M. C. SMITH.

BOTTLE CAP.

1,402,441.

Specification of Letters Patent. Patented Jan. 3, 1922.

Application filed June 27, 1921. Serial No. 480,392.

To all whom it may concern:

Be it known that I, EDWIN A. PETERSON, a citizen of the United States, and residing at Madison, Dane County, State of Wisconsin, have invented certain new and useful Improvements in Bottle Caps, of which the following is a specification.

The invention relates to improvements in closures for bottles and jars of the type illustrated in U. S. Patent No. 934,832 granted to C. C. Parker September 1, 1909. Such closures are commonly termed bottle caps and are principally used for sealing milk bottles. In the manufacture and use of caps such as shown in said patent, it has been found that the lifting tab is liable to tear off when extracting the cap from the bottle unless the cap is made of tough and rather expensive material. This is due to the fact that in the cap shown in said patent the staple protects the middle portion of the tongue only leaving the side edges free to tear at the ends of the U-shaped cut which outlines the tab. It is further due to the fact that when the tab is pulled the under layer of the cap takes all of the strain on the staple, the upper layer constituting the tab. For the above reasons it has been found that the tabs frequently tear off due to the weaknesses described and to carelessness in pulling the tab more at one side than the other.

The present improvement consists in securing the tab by two staples arranged to bridge the ends of the U-shaped cut. This results in preventing the tab from tearing at the ends of the cut, and it results in a stronger construction as one end of each staple is anchored in the cap outside of the tab so that the strain tending to dislodge the staple is resisted by the full thickness of the cap instead of by only one-half of the thickness, as in the Parker patent. The maximum strength of the tab may therefore be utilized to dislodge the cap. The invention is illustrated in the accompanying drawings in which:

Fig. 1 is a plan view of a bottle cap illustrating the invention;

Figs. 2 and 3 are similar views illustrating different applications of the invention;

Fig. 4 is a section on line 4-4 of Figure 1; and

Fig. 5 is a section on the line 5-5 of Figure 1.

Referring to the drawings 10 indicates the cap or closure which is usually a disk and preferably made from a single thickness of paper board or pulp board. The tab 11 may be formed by cutting partially through the body of the cap along the outline of the tab 60 and slightly along the tab, as described in the Parker patent. In the manufacture of the caps the tab is slit from the body of the cap and again pressed into the recess, as shown in Figures 1 to 3, so that the caps 65 can be compactly assembled in tubes for shipping purposes. To facilitate raising the tab when extracting the cap from the bottle a slight recess 12 is pressed in the cap adjacent the free end of the tab in the course 70 of manufacture. This permits the user to insert a finger nail under the tab and raise it without difficulty.

According to the present invention the hinge end of the tab is protected and 75 strengthened by two staples, one across each end of the U-shaped cut which outlines the tab. As shown in Figures 1, 4 and 5 staples 13 have their outer ends passing through the cap outside of the tab so that the full 80 strength of the cap resists the dislodging of these outer ends of the staples. The inner ends of the staples are close together so that the two staples form a nearly continuous reinforcement along the hinge edge of the 85 tab.

As shown in Figure 2 short staples 13^a are used to bridge the ends of the U-shaped cut at the hinge of the tab. These short staples may be used when the cap is made of a good 90 quality of paper board but by the use of the longer staples shown in Figure 1, or of the arrangement shown in Figure 3, a somewhat cheaper board will give satisfactory results.

As shown in Figure 3, the short staples 13^a 95 are supplemented by a third staple 14 arranged along the hinge of the tab at its middle portion and in line with the staples 13^a.

It will be apparent that in each of the forms of my invention the hinge of the tab 100 is strengthened and the tab is prevented from tearing at the ends of the U-shaped cut even though it be pulled more on one side than the other. It will also be apparent that the staples 13 and 13^a are more securely 105 anchored than the staples in the patent referred to, inasmuch as the outer end of each staple is secured in the body of the cap and

its removal resisted by the full thickness of the cap.

Having thus described the invention what is claimed as new and desired to be secured 5 by Letters Patent is:

1. A bottle cap having a lifting tab which is formed by horizontal splitting and raising of a portion of the cap in combination with two staples in line with the hinge of the tab 10 and arranged across its margin to prevent tearing at the hinge.

2. A bottle cap having a lifting tab which is formed by horizontal splitting and raising of a portion of the cap in combination with 15 two staples arranged along the hinge edge of the tab the inner ends of the staples passing through the hinge of the tab and the

outer ends of the staples passing through the body of the cap outside of the tab.

3. A bottle cap having a lifting tab which 20 is formed by horizontal splitting and raising of a portion of the cap in combination with two staples arranged along the hinge edge of the tab the inner ends of the staples passing through the hinge of the tab and the outer 25 ends of the staples passing through the body of the cap outside of the tab, the inner ends of the staples being adjacent and the staples extending along the greater portion of the hinge of the tab.

In testimony whereof I hereunto affix my signature.

EDWIN A. PETERSON.
